1,983,150

ELECTRIC CIRCUIT BREAKER

Ira B. Sigman, Alameda, Calif., assignor of one-half to Nellis A. Simonsen, Alameda, Calif.

Application May 18, 1931, Serial No. 538,016

6 Claims. (Cl. 200—152)

The invention relates to electric circuit breakers capable of being used for interrupting currents.

The breaking of an electric circuit carrying a 5 large current load is one of the most serious problems that confronts a power distributing system. The breaking of such a circuit is generally accompanied by arcing, burning of contact points and other characteristics which are ruinous to the 10 circuit breaking apparatus and invariably introduce undesirable electrical effects in the power lines.

An ideal circuit breaker would be one that would on interrupting the flow of current, place 15 a high insulating medium into the circuit, and quench any arc that may be formed, in a minimum length of time. To meet these requirements, manufacturers have concentrated their efforts on the development of a breaker which is characterized by the separation of solid conductors in a 20 fluid insulating medium. Perhaps the most successful breaker of this type is the commonly used oil breaker wherein copper contact points are separated while completely submerged in oil. Oil 25 is used as an insulating medium between the contacts and serves to occlude the air, which action reduces the burning of the copper or other electrodes to a minimum. This type of breaker has several defects. Due to the comparatively low 30 dielectric strength of oil, the contact points are necessarily drawn apart for a considerable distance when a high voltage line is to be broken. This feature necessitates the use of a large sized tank for housing the apparatus. Further the oil 35 having the best insulating properties also has a high viscosity which produces a strong resisting force to the movement of any body through the oil and thus it is almost impossible to widely separate the contact points with any great velocity. It 40 is considered good operation to completely open a circuit under load with such a breaker in approximately five to eight sixtieths of a second which would constitute a five to eight cycle period on a line operating from a source using a frequency of 45 sixty cycles a second. Further due to the vaporizing and burning of the oil intermediate the arc, a very high pressure is created, and accordingly a heavily built tank casing is required to prevent bursting of the breaker. It has also been found 50 that a breaker is often rendered inoperable due to the fusing of the copper contacts which may result from an excess load passing through the breaker.

To obviate these many defects, I have conceived and developed the idea of reversing the

basic characteristic of the previous breaker by employing in my device a fluid conductor and a solid insulator, wherein the continuity of an electric current could be interrupted by the severing of a conducting fluid column by a solid insulator. 60 Due then to this combination, my breaker provides several notable advances over the previous type of breaker.

Firstly, glass or the like which affords a gain in dielectric strength of about three times over 65 the oil may be employed as an insulation medium. This gain in the dielectric strength of the insulating medium between the electrodes obviously will reduce the necessary distance that the electrodes must separate in my breaker to 70 about one third the separating distance required in the oil type of breaker.

Secondly, in my device there is only a small 75 shearing force of the liquid column and a slight bearing friction force acting to resist the separation of the contact points, and thus the circuit may be completely opened in an extremely short interval of time.

Thirdly I may use a liquid conductor such as mercury which on being severed while under a 80 load will produce an arc causing the formation of a vapor possessing the characteristic of being strictly unidirectional in its conduction of an electric current. This last feature is very beneficial in the breaking of an alternating current circuit for should the arc last eight sixtieths of a second on a sixty cycle system, only four complete cycles or eight half cycles would be conducted during the duration of the arc. This unidirectional feature also helps materially in the 85 quenching of the arc, since should the arc form on a positive half cycle, it will disappear on the following negative half cycle, and thus on a 60 cycle system there would be a period of 1/120 of a second in which to place enough insulating 90 material between the contact points to prevent the arc from being reestablished on the following positive half cycle. Further a liquid conductor such as mercury has none of the defects as cited against the solid contacts, as there is no 95 possibility of my apparatus ever becoming inoperable due to burned or fused contacts. It should also be clear that the liquid conductor could easily and quickly be drained from the apparatus and fresh liquid substituted therefor without incurring 100 any great loss of time and without disassembling the breaker.

The invention also possesses other features of advantage, some of which, with the foregoing, will be set forth in the following description of 110

the preferred form of the invention which is illustrated in the drawing accompanying and forming part of the specification. It is to be understood, however, that variations in the showing made by the said drawing and description may be adopted within the scope of the invention as set forth in the claims.

Referring to the drawing:

Figure 1 is a sectional view of a unit built in accordance with my invention.

Figure 2 is a sectional view of a modified form of the unit shown in Figure 1.

Figure 3 is a side elevation of a different form of my invention.

Figure 4 is a plan view of a switch illustrating still another form of my invention.

Figure 5 is an end sectional view taken on the line 5-5 of Figure 4.

Figure 6 is a fragmentary plan view of a modified form of the unit shown in Figure 4.

The unit of my invention, as illustrated in Figure 1, comprises a fluid conductor 7 such as mercury confined in an insulating casing 8 which is of such structure as to provide two fluid reservoirs 9 interconnected by a column 10. The casing 8 also provides two hollow cylinders 12 and 13 of which cylinder 13 extends through the column 10 while cylinder 12 is positioned at one side of the column and is connected thereto by a small passage 14. Mounted for reciprocation in the cylinder 13 is a piston valve 16 arranged to sever the fluid column 10 and made of a material of high dielectric strength such as glass. The piston carries a lateral bore 17 through which the fluid may form an unbroken connection between the reservoirs when the piston is so positioned as to dispose a portion of the bore 17 in engagement with the column 10. In the cylinder 12 is slidably mounted a piston 18 which has connection with the fluid on its inside face and is arranged to vary the pressure on the fluid system upon movement of the piston 16 to establish or sever communication between the reservoirs 9. The desirability of varying such pressure is to assist in the most effective making and breaking of connection of the fluid column. At the instant of connection of portions of the fluid column the presence of small quantities of gas or vapor entrapped between the columns would impair connection and perhaps produce an arc causing the further formation of gas or vapor between the fluid portions. To insure the proper closing of the fluid portions, such portions are preferably urged into closed position under the pressure produced by the piston 18. On the other hand at the instant of break, an arc forms producing a conductive mercury vapor. The conductivity of such vapor is proportional to the vapor pressure. Accordingly to reduce the conductivity of such vapor and to thereby facilitate the breaking of the electric circuit, the pressure at the instant of break is preferably relieved and comparably low. To establish the desired relation between the movement of the two pistons whereby a relatively high pressure will be exerted on the fluid system at the instant of make and a relatively low pressure at the instant of break, a coupling mechanism is employed comprising a helical spring 19, a lever 20 and a connecting rod 22. Preferably the spring 19 lies between the lever 20 and the piston 16 and the connecting rod forms a tie between the lever and the piston 18. Movement of the piston 16 to place the bore 17 in registration with the column, effects a movement of piston 18 to place the fluid in communication with cylinder

12 under pressure and movement of the piston 16 to sever the fluid column releases the pressure on the piston 16 and accordingly on the fluid.

Any suitable means may be provided for actuating the piston 16. As here shown, the mechanism comprises a lever 25 pivoted intermediate its ends to the casing as at 27 and having one end in engagement with piston 16 and its other end fastened to a crank wheel 23 through the link 24. As will be clear from Figure 1, rotation of the wheel 23 will produce oscillation of the lever 25 to cause a corresponding movement of the piston.

A suitable electric circuit through the breaker is afforded through the medium of a set of suitable terminals 28 and two associated electrodes 29. The latter are embedded in the casing and extend into the fluid reservoirs 9. Leads 30 serve to connect the terminals to the electrodes.

It will now be clear that on displacement of the piston 16 to place the bore in or out of communication with the columns, the column portions on each side of the piston will be either connected or separated to thereby make or break an electric current passing through the column between the electrodes.

In Figure 2 wherein a modified form of the unit of my invention is disclosed, the mode of operation is nearly the same as that described for the apparatus shown in Figure 1. In this embodiment a tapered valve plug 32 is rotatably mounted in a correspondingly tapered seat provided in the casing member 33. As in Figure 1, a fluid column 34 is arranged to be severed by the plug 32 which carries a lateral bore 35. Two electrodes 37 are embedded in the casing and extend into the fluid column on either side of the plug member. On rotating the plug, the bore 35 may be passed into or out of registration with the column to thereby make or break a continuous path of conducting fluid between the electrodes. A cam 38 is carried by the plug and actuates a pair of pistons 39 for placing the fluid under pressure during the instant of fluid connection between the electrodes.

I have illustrated still another modified form of my invention in Figure 3. This structure comprises a casing member 41 having a portion which provides a semicircular bearing surface 42 for a movable member 43 pivoted intermediate to the casing as at 44 and having one extremity 46 seating in the bearing surface 42. The opposite end of the movable member forms a handle 47 for conveniently actuating the member. Formed in the casing and opening onto the bearing surface 42 are two bores 48. A trough 49 is formed in the end 46 of the movable member and is of such length as to be simultaneously in registration with the two bores 48. With the trough and bores filled with a conducting fluid and in registration with each other, a continuous column of fluid may form between electrodes 50 provided in the bores, and thus an electric circuit is completed through the switch. It should further be clear that on moving the handle 47 the trough may be shifted from engagement with one of the bores and the electric circuit through the switch thereby opened.

In Figures 4, 5 and 6 an embodiment of my invention is shown wherein three circuits may be simultaneously opened or closed. In this arrangement, an elongated tapered valve plug 51 is slidably carried in a seat 52 formed in the casing 53. At each side of the seat and connected thereto by passages 56, are reservoirs 54. On sliding the plug in the seat, lateral passages 55

- provided in the plug, move into or out of registration with the passages 56, whereby a continuous or interrupted column of fluid will be formed between the electrodes 57 which as here shown are submerged in the reservoirs 54. Preferably a flat spring 58 is fastened to the casing directly over the seat and slidably engages the plug member 51 to maintain the latter in seated position.
10. In order to provide a switch that will carry a heavy load an embodiment of my invention as submitted in Figure 6 may be used. In this form of the invention copper blocks 61 and 62 are shunted across the fluid path and are so positioned respectively on the casing 63 and on the plug member 64 as to arrive in operative engagement after the circuit has been closed through the fluid, and to disengage before the circuit is opened by the breaking of the fluid column.
15. To insure a smooth working switch, a very thin film of lubricant such as oil may be used for providing a substantially air tight seal between the sliding parts, and because of the extremely small cross section of such a film, its conductivity is negligible. The film will also serve in some cases to prevent the adhesion of the liquid conductor to the insulator. Further, and of considerable importance is the functioning of the oil in filling the space between the movable breaker parts and in occluding from such space air as well as other gas or vapor generated by the breaking of the circuit, thereby replacing such air or vapor with a medium of considerably higher dielectric strength and consequently increasing 35 the voltage breaking capacity of the breaker.
20. In view of the foregoing it will be clear that the electric circuit breaker of my invention possesses all of the features hereinbefore referred to and is well adapted to accomplish the elimination of 40 the defects inherent in the previous types of breakers as aforementioned.
- I claim:
1. In a device of the character described, a casing arranged to contain an electric conducting fluid, a valve for separating said fluid into electrically disconnected portions and for allowing said portions to be electrically connected, electrodes for each of said portions, and means for increasing the pressure on said fluid during the instant said valve opens to allow a continuous column of fluid to form between the said electrodes.
2. In a device of the character described, a casing arranged to contain an electric conducting fluid, a valve separating said fluid into electrically disconnected portions in closed position, electrodes for each of said portions, and means for lowering the pressure on said fluid as the valve reaches closed position.
3. In a device of the character described, an electric conducting fluid column, means operative to alternately interrupt and reestablish the continuity of said column, and means for effecting a change in pressure exerted upon the fluid in said column upon operating said first named means.
4. In a device of the character described, an electric conducting fluid column, means for alternately interrupting and reestablishing the continuity of said column, and means operative solely upon reestablishment of said continuity to exert an increase of pressure upon the fluid in the column.
5. In a device of the character described, an electric conducting fluid column, means for alternately interrupting and reestablishing the continuity of said column, and means for exerting an increase of pressure on the fluid in the column to insure an effective reestablishment of the continuity of said column upon said first named means reestablishing said continuity.
6. In a device of the character described, an electric conducting fluid column, means for alternately interrupting and reestablishing the continuity of said column, and means for lowering the pressure on the fluid in the column upon operation of said first named means to interrupt said continuity.
